METHOD OF TYING MATTRESSES

Edward L. McRoskey, San Francisco, Calif.

Application June 24, 1931. Serial No. 546,576

9 Claims. (Cl. 45—138)

The present invention relates to improvements in methods of tying mattresses, and it consists of the steps of the method hereinafter described and claimed.

5 An object of my invention is to provide a method for tying mattresses, which is an improvement over my copending application, filed April 25, 1930, and identified as Serial No. 447,281 and the present application is a continuation in part 10 of the copending application.

It is particularly proposed in the present invention to carry out the tying operation without the use of tufts or buttons. Twine or tape serves as the tying strands, and I arrange the stitch 15 span of uniform length and at predetermined intervals in parallel rows. The length of the twine or tape is determined by novel gauging means hereinafter described so as to produce a mattress of uniform thickness and tension and eliminate 20 the strand waste from present tufting methods.

The strands are drawn through the mattress while the latter is in a compressed state, and the ends of the strands are then tied together over a gauge. The knot is subsequently moved 25 so as to dispose the same on the interior of the mattress, thus enhancing the appearance of the finished mattress.

Other objects will appear as the specification proceeds, and the novel features will be pointed 30 out in the appended claims.

My invention is illustrated in the accompanying drawing, forming a part of this application, in which

Figure 1 is a plan of a mattress making device 35 which I employ, parts being broken away so as to disclose the mattress;

Figure 2 is an elevation thereof; and

Figures 3 to 6, inclusive, illustrate the successive 40 stages through which the mattresses pass during the tying operation. Figure 6 also shows a slight modification of the finished product.

In carrying my invention into practice, I make use of a mattress compressing device 1, and comprising upper and lower frames A and B, respectively, having a plurality of aligned cups 2 secured thereto, and means indicated generally at 3 for moving the frames toward and away from each other. Guides 4 are arranged in the manner shown in Figure 1 so as to maintain the 50 frames in parallel relation during the movement of the latter.

It will be noted that threaded rods 5 are rotatably carried by the lower frame, and extend through threaded openings in lugs 6, the latter 55 being anchored to the upper frame. Any suit-

able means (not shown) may be employed for rotating the rods in unison. The upper frame is raised or lowered in accordance with the direction of rotation of the rods. The entire structure is revolvably supported in bearings 7, the latter being carried by standards 8. One means for moving the frames toward and away from each other is shown in my copending application, Serial No. 447,281, filed April 25, 1930, on a Mattress making machine.

The frames preferably consist of longitudinally and transversely extending bars 9 and 10, respectively, which are secured together at their intersections so as to provide a grid having substantially square openings 11 therein. The cups 70 2 are mounted on the frames in alternate squares with the cups in one row staggered relative to those in the adjacent row. These cups are disclosed as being pyramidal in shape, and it will be observed that the cups in the two frames are 75 aligned, and are adapted for compressing a mattress 12 therebetween.

The parts thus far described form no part of the present invention, except insofar as they cooperate to produce the steps of the method.

It will be seen that the cups automatically indent the mattress on both sides simultaneously at all places where tying strands are to be secured, and that the compressed areas are disposed in longitudinal and transverse alignment 85 at regularly spaced intervals.

Slots 13 are fashioned in the bottom 14 of the pyramidal-shaped cups, and serve as guide means for allowing the introduction of a needle 15 through the mattress. A tying strand C, which 90 may be tape, twine, ribbon or other suitable material, is threaded through the eye of the needle, and drawn downwardly through the mattress adjacent to one end of the slot. The strand is then reentered, and drawn upwardly to the initial surface of entrance. The strands thus present U-shapes, and the legs of the U are spaced by the length of the slot 13. The spacing of the legs determines the stitch span.

In Figures 1 and 4, I show a gauge 16 arranged 100 over two adjacent bars 10 of the upper frame. The gauge is curved in transverse section, and also tapers from the central portion toward the ends thereof. The free ends of the strands are tied over the top of the gauge at 17 while the 105 mattress is compressed. The gauge assures the operator that all of the strands are of the same height, and that the mattress will be of a uniform thickness and tension when released from the apparatus.

- The ends of the knotted portion are now trimmed, and the gauge removed. The endwise taper of the gauge facilitates the withdrawal of the same from the looped part of the strand.
- 5 Subsequently, the operator moves the strand in the direction of the arrow *a* in Figure 5 in order that the knot 17 may be accommodated within the interior of the mattress, and thus be hidden from view.
- 10 After all of the strands are tied and turned in the manner just described, the frames A and B are separated, and the mattress shown in Figure 6 results. The mattress may be of any conventional construction, and in this latter figure, I have diagrammatically shown a portion of a

15 spring filled mattress.

From the foregoing description of the various parts of the apparatus and the steps included in the method, the operation of the same may be readily understood. The exposed looped ends of the tying strands or the stitch span are uniform in length and are disposed in alignment at spaced intervals. Moreover, the lengths of the strands are equal, and a uniform thickness of mattress

20 results.

The tape, ribbon or the like may be carried on a spool, and it is not necessary in the present method to cut the strands into predetermined lengths before they are applied to the mattress.

25 30 The gauge and the space between the frames A and B automatically determine the proper length of all of the strands.

While I have shown only the preferred form of the invention it should be understood that various changes or modifications may be made within the scope of the claims hereto attached, without departing from the spirit of the invention.

I claim:

1. A tufting machine comprising mattress-compressing members for designating the places to be tufted throughout the entire mattress, and a removable gauge for determining the length of the looped strand in the mattress.
- 40 45 50 55 60 65 70 75 80 85 90 95 100 105 110 115 120 125 130 135 140 145 150
2. The herein described method of tying a mattress which consists in simultaneously compressing the same at spaced points, drawing strands through the compressed sections one at a time to form loops having their free ends projecting from one face of the mattress and tying the ends

of each loop at a uniform distance away from the mattress.

3. A machine of the character described comprising a pair of coacting frames having means for simultaneously compressing a mattress at spaced points and means for supporting a tie gauging member relative to each point of compression.

4. A machine of the character described comprising a pair of coacting frames having means for simultaneously compressing a mattress at spaced points and bars arranged on one of said frames on opposite sides of each point of compression for supporting a tie gauging member thereon.

5. The method of tufting a mattress comprising the steps of simultaneously compressing a mattress at spaced points and of passing tufting elements through the mattress at the spaced points one at a time.

6. The method of tufting a mattress comprising the steps of simultaneously compressing a mattress at spaced points, of passing tufting elements through the mattress at the spaced points one at a time and of gauging each element for uniform length with the other elements.

7. The method of tufting a mattress comprising the steps of simultaneously compressing a mattress at spaced points, of passing tufting elements through the mattress at the spaced points one at a time, and of gauging the secured length of each element for uniform length with the other elements.

8. The method of tufting a mattress comprising the steps of compressing a mattress at spaced points while it is in horizontal position, of arranging the compressed mattress in vertical position and of securing tufting elements in the mattress at the spaced points while the mattress is held in vertical position.

9. The method of tufting a mattress which comprises the steps of compressing the mattress at spaced points while it is in a horizontal position, of arranging the compressed mattress in vertical position, of securing tufting elements in the mattress at the spaced points, of returning the mattress to horizontal position and of releasing the mattress.

EDWARD L. MCROSKEY.
